WILLIAM SHAW, OF LAKEWOOD, OHIO, ASSIGNOR TO CARBON COMPANY, OF CLEVELAND, OHIO, A CORPORATION OF OHIO.

PIGTAIL CONNECTION.

1,147,451.

Specification of Letters Patent. Patented July 20, 1915.

Application filed October 15, 1912. Serial No. 725,850.

To all whom it may concern:

Be it known that I, WILLIAM SHAW, a subject of the King of England, and a resident of Lakewood, in the county of Cuyahoga, in the State of Ohio, have invented new and useful Improvements in Pigtail Connections, of which the following is a clear and exact description.

This invention relates to connections for 10 brushes on dynamo-electric machines commonly called "pigtail" connections.

One object of the invention is to secure the conductor to the brush with minimum contact resistance.

15 Another object is to secure the conductor to the brush so that it cannot work loose in practice, but to attach it in such a manner that it can be readily removed, and attached to another brush when the first one is no 20 longer serviceable.

Other objects will appear in the appended description.

In the drawings: Figure 1 is a section of a spun tube from which clips are made. 25 Fig. 2 is a view of the clip after the pigtail has been inserted in the tube shown in Fig. 1 and compressed. Fig. 3 is a top view of the connection shown in Fig. 2. Fig. 4 is a modified form of clip. Fig. 5 is

30 a view of a brush before the pigtail is attached. Fig. 6 is a view of the brush with the clip shown in Fig. 3 attached thereto. Fig. 7 is a view of a brush with the clip shown in Fig. 4 attached thereto. Fig. 8

35 is a section on the plane A—A of Fig. 6. Fig. 9 is a view of a modified form of brush before the pigtail is connected thereto. Fig. 10 is a view of the brush shown in Fig. 9 with the pigtail attached. Fig. 11 is a section 40 taken on the line B—B of Fig. 10. Fig. 12 is a view of the nut used to clamp the pigtail in Fig. 10. Fig. 13 is a modified form of connection. Fig. 14 is a section of a slightly different form.

45 Referring to Fig. 1, if a section of a tube 1 be spun down at one end as at 2, a conductor inserted through the reduced opening, and the tube pressed together, an attractive and serviceable clip results. A side view of 50 the clip and pigtail is shown in Fig. 2. A hole 3 is formed through the clip, Fig. 3, and the same is threaded to receive a screw. The method of making this new form of clip is described in my application filed

55 Aug. 6, 1912, Serial No. 713,571, and hence

the manner in which it is made is given in this application only in a brief way. This form of clip is easily made and gives a very attractive strong connection. It might seem that if a hole were threaded through such a 60 clip that it would not be strong enough to serve as a nut to clamp the connection to the brush, but it has been found that the clip will serve as a nut and makes a strong 65 connection. The small wires of the pigtail which are compressed between the sides seem to be rigidly held in place so that they help form the threads.

A brush 4, Fig. 5, has a hole 5 formed 70 through it and a channel or slot 6 is formed as shown. This channel is cut to such a depth that the clip placed in it is approximately flush or beneath the surface of the brush; so as to prevent the connection from interfering with the movement of the brush 75 in the holder. The clip 5 with the attached conductor is placed in the slot 6, Fig. 8, and drawn firmly against the brush by the screw 6'. The screw may be locked in place if desired by the bail 7 which fits in the slot in 80 the screw head. The lock may in some cases be omitted. The slot 6 need not necessarily extend to the top of the brush parallel to its sides. It may extend diagonally 85 toward the top corner of the brush.

In some types of brushes a separate metallic piece is extended over the top of the brush to serve as a rest for the spring hammer that forces the brush against the commutator. My new form of clip can be made 90 to serve both as the nut and as the hammer rest by making it of suitable length and bent to extend part way or entirely across the top of the brush. Such a clip is shown in Fig. 4 and is shown connected to the brush 95 in Fig. 7. This arrangement gives additional contact surface as the top portion 8 of the clip engages the top of the brush. In this form, as well as that shown in Fig. 6, the shape of the clip is non-circular so that 100 it cannot work loose. The bail 7 serves to prevent the screw from turning so that the connection is securely locked. When the brush is worn out the bail may be pulled out or the brush may be broken apart. The 105 screw can then be disengaged from the nut and the connection placed on another brush.

In Figs. 9, 10 and 11, I have shown a modified form of connection. The pigtail end in this case is not secured to a clip, but 110

is coiled around the screw 6' in a groove and tightly compressed therein by an angular shaped nut 10. The nut extends over the top of the brush and serves as a hammer support and furnishes additional contact surface to take the current from the brush. The prolongation of the nut also serves to effectively prevent the nut from turning. The pigtail may extend through the groove 10 or it may extend up through a straight slotted brush as in Fig. 5, and pass through a hole or notch 12 in the nut extension as in Fig. 13.

If desired the groove 9 may be omitted and the pigtail clamped by the nut 10 against the flat bottom of the slot as in Fig. 14. I prefer, however, the arrangement shown in Fig. 9 as the wires 13 are compressed in the groove 9 and give elasticity to the connection such that an expansion of the screw or other loosening will not destroy the good contact. This groove is preferably convergent as shown, though one side need not necessarily be vertical. The elastic effect could also be obtained if different shaped grooves were used.

In all the described connections the brushes, grooves and slots may be metallic coated if desired, but the connections given have a low contact resistance and such coating is not necessary.

In the claims the conductor is referred to as a pigtail. This term, however, is not to be limited to any form of pigtail, but is intended to include all forms of flexible conductors.

Having described my invention what I claim is:

1. In a current collector, a brush having a

hole therethrough terminating in a channel, 40 said channel extending to the top of the brush, a nut in the channel and a screw in said hole engaging the nut, said nut having a prolongation extending over the top of the brush, and a pigtail fastened to the prolongation. 45

2. In a current collector, a brush having a hole therethrough, a nut having a prolongation extending over the top of the brush, a screw in said hole engaging the nut and a 50 pigtail fastened to the prolongation.

3. In a current collector, a brush having a channel in one side, a current connection consisting of a clip compressed around a stranded conductor, said connection having 55 a hole therethrough with threads cut in the clip and strands of said conductor, a screw extending through the brush and secured in said threaded hole to retain the clip in the channel. 60

4. In a current collector, a brush having a channel in one side, a current connection consisting of a clip compressed around a stranded conductor, said connection having 65 a hole therethrough with threads cut in the clip and strands of said conductor, a screw extending through the brush and secured in the threaded hole to clamp the clip in said channel, and a bail in the slot of the screw head extending into the brush to prevent the 70 screw from turning.

In testimony whereof I have heretunto signed my name.

WILLIAM SHAW.
